UNITED STATES PATENT OFFICE

173,263

LEAD SIGHT FOR GUNS

Frank E. Fink, Excelsior, Minn.

Application March 23, 1953, Serial No. 24,159

Term of patent 14 years

(Cl. D30—1)

To all whom it may concern:

Be it known that I, Frank E. Fink, a citizen of the United States, residing at Excelsior, county of Hennepin, and State of Minnesota, have invented a new, original, and ornamental Design for Lead Sight for Guns, of which the following is a specification, reference being had to the accompanying drawing, forming a part thereof.

Fig. 1 is a view in perspective of a lead sight for guns, showing my new design; and

Fig. 2 is a view in elevation.

I claim:

The ornamental design for a lead sight for guns, as shown.
